UNITED STATES PATENT OFFICE.

CURT RICHARD STADERMANN AND JOSEPH C. HAMMER, OF HARTFORD, CONNECTICUT.

RETURN-COUPON LETTER-SHEET ENVELOP.

1,007,612.

Specification of Letters Patent. Patented Oct. 31, 1911.

Application filed September 29, 1910. Serial No. 584,476.

To all whom it may concern:

Be it known that we, CURT RICHARD STADERMANN and JOSEPH C. HAMMER, citizens of the United States, residing at Hartford, in the county of Hartford and State of Connecticut, have invented a new and useful Improvement in Return-Coupon Letter-Sheet Envelops, of which the following is a specification.

10 This invention relates to a letter-sheet envelop which is adapted to inclose ordinary correspondence, but which is particularly intended to be used for advertising purposes.

The object of the invention is to provide 15 a simple, cheap and conveniently sealed wrapper, attached to which and forming part thereof are several pages adapted to receive advertising matter, illustrations or correspondence.

20 The invention resides in a sheet of paper which is considerably larger than the envelop proper, and which is so shaped and creased that, after having the advertising matter printed or the correspondence written 25 ten thereon, it can be readily folded together, into the form of an envelop, and easily secured by gummed flaps that are attached to the section which forms the front side of the envelop.

30 Figure 1 of the accompanying drawings shows a front view of the unfolded envelop blank. Fig. 2 shows a view of the other side of the same. Fig. 3 shows a back view of the envelop folded and ready for mailing. Fig. 4 shows a front view of the folded envelop in the same condition.

The blank from which this envelop is formed is cut from a sheet of paper of the necessary size and desired weight and quality. The section 1 of the blank is that which forms the front side of the envelop when folded and ready for use. This section is bounded by the creased lines 2. At two ends and one side of this section are flaps 3, that are gummed on the back face. On the front face of this section, in the usual corner, is a space 4 for the necessary postage stamp. The section 1 at its lower edge is attached to the section 5 which forms the back side 40 of the envelop when folded. The lower edge of the section 5 is attached to the section 6, the division being the creased line 7. Attached to one end of the section 5 is a section 8 and attached to the same end of the section 6 is a section 9. Attached to the other end of the section 5 is a section 10, and at-

tached to that end of the section 6 is a section 11. These sections are separated by the creased line 12 on one side, the creased line 13 on the other side, and the creased line 7 through the middle of the sheet. The section 1 is scored or perforated on the line 14 below the stamp location, forming a coupon 15 which it is intended shall be torn off after the envelop has been sent through the mail. It is designed to print on the back of the coupon part of the section 1 such instructions as to the return of the coupon after use, as is suitable. In one use of the envelop the inner face of the section 5, and both inner and outer faces of the sections 6, 8, 9, 10 and 11 are intended to be printed with advertisements or announcements. If desired, one or more of the sections may be left blank for the purpose of allowing the user to write an order for any article which is advertised on the remaining sections. If all of the sections are covered with advertisements, it is intended to inclose within the envelop an ordinary sheet of letter paper folded to the size of the sections 1 and 5, for correspondence.

The envelop is desirably made ready for mailing by first folding the sections 8 and 9 on the creased line 12 over against the inner surface of the sections 5 and 6, then folding the sections 10 and 11 on the crease 13 over against the sections 8 and 9. Then the sections thus folded are folded on the crease 7, and finally these pages thus formed are folded on the lower crease 2 against the back of the section 1. After the sheet has been folded in this manner the gummed flaps are moistened and pressed down and caused to adhere against the back of the section 5 for sealing the envelop. The sections 5, 6, 8, 9, 10 and 11 constitute collectively the letter sheet of the device, and as shown the length of this sheet exceeds the length of the body of the envelop portion. While we have indicated one way in which this sheet can be folded we of course do not restrict ourselves to this.

It is intended to supply these envelops, with one or more of the sections blank, or containing a sheet of paper, already stamped for mailing to the advertisers who have spaces on the envelop. These advertisers dispose of the envelops to their customers, and after the envelop has been used the recipient may tear off the coupon, which as illustrated is the part 15 of the section

1 to which the stamp and post-mark have
been applied and redeem the coupon and re-
ceive a predetermined sum in cash or credit
from any of the parties whose advertisement
5 appears on the envelop.

From the foregoing description it will be
evident that the body of the envelop of our
combined letter sheet and envelop, has a
10 coupon on the inner face and upper portion
thereof, by reason of which said coupon will
be opposite the cancellation area of the en-
velop. When the device is folded up for
transmission through the mails and with its
15 stamp, the coupon will be wholly covered
and out of view so as to thereby be pro-
tected from smears and similar things. The
coupon, however, will be opposite the can-
cellation portion of the envelop. This cou-
20 pon represents value but only when the cou-
pon portion has been postmarked and can-
celed. Before, therefore, a coupon can be
redeemed it must bear indication that it
has passed through the mails. The can-
25 cellation of the stamp will ordinarily be an
attestation of this fact; the postmark, how-
ever, will assure the same. A redeemable
coupon, therefore, which is ultimately sepa-
rated from the combined letter sheet and
30 envelop will bear on one side printed matter
indicating that it is redeemable for value or
something of an equivalent nature and on
the other face will carry the stamp cancella-
tion and postmark or either of them. As a

matter of facilitating the separation of the
coupon portion we prefer as already indi-
cated to score the body of the envelop, the
score lines extending from one side edge to
the other side edge of said body. This
scoring, as will be inferred, divides said
body into two distinct portions, one a super-
scripture portion and the other a coupon
portion, the inner face of the latter bearing
the printed directions to which allusion has
already been made and being located above
the superscription portion.

45 The invention claimed is:

1. A combined letter sheet and envelop,
the body of the envelop having a coupon on
the inner face and upper portion thereof,
whereby said coupon will be opposite the 50
cancellation and postmarking portion of the
envelop.

2. A combined letter sheet and envelop,
the body of the envelop having a score line
extending from one side edge to the other 55
side edge thereof, thereby dividing said
body into superscription and coupon por-
tions, the coupon portion having printed di-
rections on the inner face of said body and
being located above the superscription por- 60
tion.

CURT RICHARD STADERMANN.

JOSEPH C HAMMER.
